UNITED STATES PATENT OFFICE.

ALLAN CLARK, OF SEATTLE, WASHINGTON.

RADIATOR.

Application filed February 28, 1923. Serial No. 621,772.

To all whom it may concern:

Be it known that I, ALLAN CLARK, a citizen of the United States of America, and resident of the city of Seattle, in the county of King and State of Washington, have invented certain new and useful Improvements in Radiators, of which the following is a specification.

My invention relates to radiators and particularly to an improved radiator, which may be moved about from place to place in a room or from one room to another, carrying its own steam generating unit peculiarly designed for use with it, so that heat may be generated quickly and distributed where desired.

It is an object of my invention to provide a steam generator or boiler which is particularly designed and particularly applicable for use in conjunction with such a portable or mobile radiator.

My invention comprises those novel parts and combinations thereof which are shown in the accompanying drawings, described in the specification and particularly defined by the claims terminating the same.

In the accompanying drawings my invention is shown in the form which is now preferred by me, although changes may be made therein, within the scope of the claims.

Figure 1 is a general elevation of a radiator, boiler and support therefor, embodying my invention.

Figure 2 is a longitudinal section through the boiler forming a part of my invention.

Figure 3 is a transverse section through the boiler and the support therefor, on the line 3—3 of Figure 2.

It is often desirable to provide steam heat in a single room or in certain rooms of a house without the necessity of firing a large boiler of capacity sufficient to heat the entire house, and further, to position the radiators at such points as will most satisfactorily heat the room. It is also desirable that these radiators be portable or mobile readily, and that they be as inconspicuous as possible, and pleasing in appearance. They should also be readily controllable as

to the degree of heat, and so designed that steam is quickly generated and available in the radiator columns. To these ends I have produced my invention, a preferred embodiment of which is shown in the drawings.

In the form shown herein the radiator 1 is of a stock size and design, and it is my

intention to provide supports which are adapted for use with stock radiators. The feet 10 of the radiator rest upon a suitable support 2, which is in reality a mobile carriage, being mounted upon casters 20. Preferably this box-like carriage 2 is open at one end, and this opening may be closed by a door 21.

Wholly or partly within the carriage 2 I secure a steam boiler. This is best shown in Figures 2 and 3. Herein the boiler is shown as comprising an outer shell 3 having a rounded bottom 30 and a steam dome 34 above the water line. The boiler shell 3 is secured in some suitable manner within the supporting carriage 2, as by means of rivets or bolts 32 securing its feet 31 to the bottom of the carriage 2. The ends 33 of the boiler shell, or at least a portion thereof, may be inclined upwardly and inwardly to form the steam dome 34 within the upper portion of the boiler shell. From this steam dome extends one or more, preferably two, steam outlet conduits 35. These conduits are of any suitable shape and design, and extend upward to connections at the ends of the radiator 1, these being the usual connections provided in radiators for the steam pipes. By means of these or other suitable connections the radiator 1 is secured rigidly upon the carriage 2, its feet 10 resting upon the upper surface 21 of the carriage.

Within the boiler shell 3 I secure a tube 36 which is open at at least one end, this being the end corresponding to the open end of the carriage 2. The tube 36, which receives a heating element 4, is eccentrically placed relative to the rounded bottom 30 of the boiler shell 3, its center being below the center of the rounded bottom 30. By this means I provide a water jacket entirely surrounding the tube 36 but of greater thinness at the bottom than at the sides. By this means the cooler water, which will sink to the bottom, being spread out more thinly than the warmer water at the sides, will be more readily heated, and in this way the efficiency of the boiler and the rapidity of its action is increased.

The heating element 4 may be of any suitable design. Such heating elements are common in the electrical art, and as the particular design forms no part of the present invention, I shall not describe it in greater detail. The electrical connections 41 lead

ing therefrom are connected to a variable resistance switch 42 placed upon the outside of the carriage 2 to permit ready control of the heat.

5 It is my intention to provide but a small amount of water in the boiler, thus reducing the time required to generate steam, and making for lightness of the radiator. I have found that it is desirable to maintain the heating element at all times surrounded with water, to the end that it will not become overheated. I therefore provide a filling opening 39 which is closed by a plug 37 opening into the interior of the boiler shell 3. This filling opening is located above the upper level of the tube 36 and at about the bottom of the steam dome 34. If the escape valve 11 of the radiator is closed (providing such a valve is employed) the space 20 above the filling opening and plug 37 will be dead space, and no more water will enter the boiler shell than that which lies below the level of the plug 37. By this means I control the maximum amount of water to be placed in the boiler and insure that the water level will not be so high above the tube 36 that the tube will be covered to too great a depth. In order to observe the water level in use, I may provide the water gage glass 38 outside of the casing 2, where it is readily visible.

It will be noted that a device of the character described is simple, compact, and of a not displeasing design. The controls are 35 simple and yet effective, and convenient to operate. The radiator may be placed at any desired point and by reason of the small amount of water in the boiler, and because of the position of the heating element in the 40 boiler, the radiator will begin to heat within

a short time after turning on the current in the heating element 4. If it is necessary to remove or replace the heating element, this may be done quickly by opening the door 21, disconnecting the leads 41 from the heating element, and withdrawing the latter from the tube 36, a new element being similarly replaced. The boiler itself is rigidly secured to the carriage 2 and through this boiler the radiator 1 is rigidly secured to the 50 carriage, permitting the entire device to be moved about at will.

What I claim as my invention is:

1. A steam boiler for individual steam radiators comprising a rounded bottom shell 55 having a tube extending therethrough near its bottom, said tube being of slightly less diameter than the diameter of the shell's bottom, and being eccentrically positioned relative thereto, with its center lower than the center of the shell's bottom, and a heating element removably positioned in said tube.

2. A steam boiler for individual steam radiators comprising a rounded bottom shell having a tube extending therethrough near its bottom, said tube being of slightly less diameter than the diameter of the shell's bottom, and being eccentrically positioned relative thereto, with its center lower than the center of the shell's bottom, a steam dome formed by inclining inwardly and upwardly the ends of said shell, a filling opening located above said tube and below the steam dome, and steam outlets leading upwardly 75 from said steam dome.

Signed at Seattle, King County, Washington, this 23rd day of February, 1923.

ALLAN CLARK.
